CLAIM

I claim the ornamental design for a seamless leather skullcap, as shown and described.

DESCRIPTION

FIG. 1 shows a top front side perspective view of a first embodiment of a seamless leather skullcap;
FIG. 2 shows a front side view of FIG. 1;
FIG. 3 shows a back side view of FIG. 1;
FIG. 4 shows a left side view of FIG. 1;
FIG. 5 shows a right side view of FIG. 1;
FIG. 6 shows a top view of FIG. 1;
FIG. 7 shows a bottom view of FIG. 1;
FIG. 8 shows a top front side perspective view of a second embodiment of the seamless leather skullcap;
FIG. 9 shows a front side view of FIG. 8;
FIG. 10 shows a back side view of FIG. 8;
FIG. 11 shows a left side view of FIG. 8;
FIG. 12 shows a right side view of FIG. 8;
FIG. 13 shows a top view of FIG. 8;
FIG. 14 shows a bottom view of FIG. 8;
FIG. 15 shows a top front side perspective view of a third embodiment of the seamless leather skullcap;
FIG. 16 shows a front side view of FIG. 15;
FIG. 17 shows a back side view of FIG. 15;
FIG. 18 shows a left side view of FIG. 15;
FIG. 19 shows a right side view of FIG. 15;
FIG. 20 shows a top view of FIG. 15;
FIG. 21 shows a bottom view of FIG. 15;
FIG. 22 shows a top front side perspective view of a fourth embodiment of the seamless leather skullcap;
FIG. 23 shows a front side view of FIG. 22;
FIG. 24 shows a back side view of FIG. 22;
FIG. 25 shows a left side view of FIG. 22;
FIG. 26 shows a right side view of FIG. 22;
FIG. 27 shows a top view of FIG. 22; and,
FIG. 28 shows a bottom view of FIG. 22.
The broken lines depict features of the seamless leather skullcap that form no part of the claimed design.

1 Claim, 28 Drawing Sheets
